UNITED STATES PATENT OFFICE.

FRANK S. CHURCH, OF DETROIT, MICHIGAN.

SMOKE-CONSUMER.

SPECIFICATION forming part of Letters Patent No. 623,858, dated April 18, 1899.

Application filed June 10, 1897. Serial No. 640,146. (No model.)

To all whom it may concern:

Be it known that I, FRANK S. CHURCH, a citizen of the United States, residing at Detroit, in the county of Wayne and State of Michigan, have invented certain new and useful Improvements in Smoke-Consumers, of which the following is a specification, reference being had therein to the accompanying drawings.

10 My invention relates to that class of smoke-consumers adapted to be applied to furnaces and comprising devices for increasing the draft whenever fresh fuel is introduced and means for restoring the normal condition of 15 draft after the lapse of an interval of time.

It is the object of my invention to obtain a simple construction of mechanism for accomplishing the object above stated and one which is adapted during its interval of operation 20 to gradually cut off the draft, so as to furnish at each instant only the draft required to prevent the formation of smoke, and thereby preventing the wasting of fuel.

The invention is embodied in the peculiar 25 construction, arrangement, and combination of parts, as more fully hereinafter described and claimed.

In the drawings, Figure 1 is a diagram front elevation of a furnace to which my device is 30 applied. Fig. 2 is a perspective view of the regulating mechanism. Fig. 3 is a section through the steam-controlling valve and its operating mechanism, and Fig. 4 is a section through the steam-nozzle.

35 A is the furnace of a steam-generator. B are the doors.

C is a steam-pipe leading to a blast-nozzle D which projects into the furnace, and E is a valve controlling the passage of steam 40 through the pipe C. This valve E is a balanced valve, preferably consisting of the casing a, the stem b passing through a stuffing-box c and carrying the two disks d and e, which have equal exposed areas on their pressure-side and are seated at f or g in the partition h.

F is a lever connected to the stem b and fulcrumed to the pivotal link G, secured to a lug or arm H on the casing.

I is a rod slidingly secured in bearings J. 50 K is a connecting-rod pivoted at one end to one end of this rod and at its other end con-

nected to the pivotal link L, which in turn is connected to the lever F.

M are cranks on the doors B, which are connected by the links N to the rod I, said links 55 being preferably bifurcated at one end to embrace the rod I, to which they are pivoted, and having slotted bearings at their opposite ends engaging with pins i on the cranks, the arrangement being such that the opening of 60 either of the doors will move the rod in one direction without interference from the other door, while the movement of the rod in the opposite direction will close both doors if they are open. 65

O is a weight for moving the rod I to close the doors. O' is a chain from which this weight is suspended, which passes over the sprocket P and is connected at its opposite end to the rod I, preferably through the medium of the bell-crank lever Q, one end of which is attached to the chain and the other end to the connecting-rod K. 70

P' is a train of gearing connected to the sprocket P through the medium of the clutch 75 S and provided with a suitable escapement or governing lever T.

The blast-nozzle D is preferably constructed as shown in Fig. 4 of the drawings, in which j is a pipe connected to and depending from 80 the furnace A' outside of the boiler-front. k is a horizontal pipe connected to the pipe j and passing through the front. l is a hollow hood or deflector connected to the pipe k. m is the steam-pipe connected to the pipe C and 85 passing centrally through the pipe k, being adapted to direct a jet of steam against the deflector l, all so arranged that the part of the nozzle and the deflector exposed to the heat is completely surrounded by a water-jacket which communicates with the boiler. 90

In the operation of the device whenever one of the furnace-doors B is opened to introduce fuel the rod I will be drawn forward by the cranks M and links N, and in turn will 95 open the valve E and draw up the weight O, the clutch S preventing the sprocket P turning as the chain is drawn over it without moving the gear-train P'. As soon as the doors are released the pull of the weight O on the rod 100 I will tend to return said rod and close the doors and the valve E; but its movement in

this direction will be retarded by the gear-train P', which constitutes a time mechanism, taking a definite interval of time to complete its movement. During this interval the doors and the valve will be correspondingly gradually moved from their open position to the position where they are completely closed. Thus the draft is strongest at first when it is most needed and gradually dies out. The object of employing a balanced valve is to permit of this gradual closing without interfering with the movement of the time mechanism, which otherwise would be caused by the pressure of steam against the valve. Should the fireman desire to open the furnace-door for any other purpose than to throw in fresh fuel, he may close the doors again immediately without waiting for the time-motor to act by reason of the lost-motion connection between the rod I and cranks M, formed by the slotted links N. He may also immediately close the valve E to turn off the steam by sliding the rod I in its bearings, the flexible chain permitting of this movement independent of the motor and the balanced valve offering no resistance. If the air admitted when the door is fully opened is more than necessary to insure perfect combustion, the fireman may partially close it after the introduction of the fuel, in which position it will remain until the movement of the motor takes up the lost motion in the link N, after which the door will be closed. Thus the draft may be regulated to suit the requirements of the furnace or the particular fuel employed.

What I claim as my invention is—

1. The combination with a furnace a door for the furnace having a blast-jet and a balanced valve controlling the same, of a rod slidingly secured in bearings, connections between said rod and the furnace-door and said balanced valve respectively, whereby the opening of said door will move said rod and open said valve correspondingly, a weight for closing said valve and door, having a flexible

connection attached to said rod, a wheel over which said connection passes, time mechanism to which said wheel is connected for retarding the closing of said valve and door and an intermediate clutch adapted to permit the free movement of said wheel when the door and valve are opened.

2. In a smoke-consumer, a blast-nozzle comprising a water-tube projecting into said furnace, a hollow hood or deflector connected with said tube and a steam-jet pipe passing through said tube and directed against said hood or deflector.

3. The combination with a furnace, two oppositely-hinged doors therefor, a blast-jet, a valve controlling said jet, connections between said doors and said valve adapted to open the latter on the opening of either door, a time-motor for gradually closing the valve and the open door, said connection between the valve and doors being such that the same can be operated manually to close the open door and valve independently of said motor, substantially as described.

4. The combination with a furnace, a hinged door therefor, a blast-jet, and a balanced valve controlling the same, of a rod slidingly mounted in bearings, a crank connected to said door, a connection between said crank and rod adapted, upon the opening of said door, to slide said rod and adapted to permit the closing of said door without affecting the rod, a connection between said rod and said valve, and a time-motor and a connection between said motor and rod adapted to move the latter to close said door and valve, said connection permitting the closing of the valve independently of the operation of the motor, substantially as described.

In testimony whereof I affix my signature in presence of two witnesses.

FRANK S. CHURCH.
